Patented Nov. 21, 1967

209,272

TOILET SEAT

Charles G. Tate, Jr., 19 Locust St.,
North Providence, R.I. 02906

Substituted for abandoned design application Ser. No.
83,706, Jan. 7, 1965. This application June 20, 1966,
Ser. No. 4,078

Term of patent 14 years

(Cl. D4—5)

FIG. 1

FIG. 2

FIG. 3

FIG. 4

FIGURE 1 is a top plan view of a toilet seat embodying my new design;

FIGURE 2 is a side elevational view thereof;

FIGURE 3 is a sectional view taken substantially on the plane of line 3—3 in FIGURE 1; and

FIGURE 4 is a sectional view taken substantially on the plane of line 4—4 in FIGURE 1.

I claim:

The ornamental design for a toilet seat, substantially as shown.
